DIE CASTING DIES

Louis H. Morin and Davis Marinsky, Bronx, N. Y.,
assignors to Whitehall Patents Corporation,
Bronx, N. Y., a corporation of New York

Application March 4, 1939, Serial No. 259,816

3 Claims. (CL. 18—42)

This invention relates to dies for use in die casting machines wherein heated thermoplastic material is injected from dual cylinders or nozzles into the impression of the dies in forming resulting die castings, each composed of two different casting materials, or materials of different colors. More particularly the invention relates to a die structure wherein two impressions are formed on adjacent surfaces of relatively movable dies with gates arranged on the parting line of the dies opening into said impressions, and further wherein one impression is smaller than the other and said other impression shaped to receive the casting formed in the first impression so that the cast body formed in the second or larger impression will be arranged upon and united with the first mentioned casting arranged therein in producing two colored die castings. The novel features of the invention will be best understood from the following description when taken together with the accompanying drawing, in which certain embodiments of the invention are disclosed and in which the separate parts are designated by suitable reference characters in each of the views, and in which:

Fig. 1 is a diagrammatic plan view showing dies in a closed position and indicating the arrangement of injection nozzles thereon.

Fig. 2 is a sectional view on the line 2—2 of Fig. 1 indicating the formation of castings in the impressions of the dies.

Fig. 3 is a section on the line 3—3 of Fig. 2 showing the dies in open position with the castings ejected and moved by a core pin employed.

Fig. 4 is a view similar to Fig. 3 showing the dies in closed position and indicating the castings formed therebetween.

Fig. 5 is a face view of one die part showing the impressions and gate passages therein.

Fig. 6 is a view similar to Fig. 2 showing a modified form of die for producing other types of castings, and

Fig. 7 is a sectional view of the resulting casting formed from the die shown in Fig. 6.

This application is a continuation in part of our prior application No. 144,627, filed May 25, 1937, now Patent No. 2,234,185 and of our prior application No. 258,928, filed February 28, 1939, and embodying a division of the subject matter originally covered in said applications. The construction shown in Figs. 1 to 5 inclusive in the present application relates to the die structure of the earlier application identified above, whereas the structure shown in Figs. 6 and 7 is based

on the die structure illustrated in the second mentioned application.

In Figs. 1 to 5 inclusive, 10, 10a represents relatively movable dies which are arranged in and operated by suitable means in a die casting machine so as to move toward and from each other and to be firmly held in engagement with each other in the casting operation to separate in ejecting the casting on a core pin 11 and then 10 partially closed in stripping the castings from the core pin. Each die part has on adjacent surfaces thereof two impressions 12, 13 which are spaced apart, the impression 12 being smaller than the impression 13 and the impression 13 being so 15 shaped as to receive the casting 14 formed in the impression 12 in successive casting operations of the machine. The enlarged portion of the impression 13 forms a cast body 15 directly upon the casting 14 when arranged in the impression, 20 and it is preferred that a dove-tailed tongue or other keying means 14a be provided on the cast body 14 so that the cast body 15 will interlock therewith as will be apparent.

In the construction shown, the resulting two-part casting, which is represented at 16 in Fig. 2 of the drawing, is in the form of a pull such as used on the sliders of separable fasteners, but of course it will be understood that any type or kind of casting can be produced in accordance 25 with the invention, the cavities or impressions 12, 13 being shaped to produce the desired finished product.

On the parting line of the dies 10, 10a is a single admission orifice 17 which opens into 35 branches 18 and 19 extending to each impression, so that when heated thermoplastic material is injected under pressure from a nozzle 20 into the gate passages 17, 18 and 19, the two cast bodies 14 and 15 will simultaneously be formed. For 40 illustrative purposes we will assume that this material is red in color, then the two cast bodies 14 and 15 will be red. Another nozzle or cylinder 21 containing a blue thermoplastic material is next moved into registering position with the orifice or passage 17 so that the next successive casting will have the bodies 14, 15 cast in blue, as is clearly illustrated and understandable from the showing in Fig. 2 of the drawing.

The impression 12, or each half of the impression is provided with inwardly projecting tongues forming core pieces 22 which form an aperture 23 in the resulting casting, that is to say, in the part 14 thereof. The impression 13 has similar core portions 24 to register with the formed aperture 23 when the part 14 is moved into the impression,

and if desired, other similar cores 25 may be provided in the impression 13 to form on the resulting casting an aperture 26 in the part 15.

It will appear from a consideration of Figs. 2 and 5 of the drawing that the lower portions of each die part 10, 10a is provided with a diagonal gate 18a similar to the branch 18 so as to receive the gate which remains on the part 12 when moved into the impression 13. This gate, including the gate formed as at 19, are trimmed from the resulting casting. Adjacent surfaces of the die parts 10, 10a are also provided with an aperture 27 leading into the impression 12 for receiving the pin 11 which acts as an ejector pin in removing the castings from the die parts when the die parts are separated and also to feed the cast body 14 into position to enter the impression 13.

Each of the die parts are provided with water circulating passages 28 as indicated in Figs. 3 and 4 of the drawing for the circulation of water or another cooling agent through the dies adjacent the impressions therein to chill the material injected into the impressions in forming the castings in accordance with known processes.

In Figs. 6 and 7 of the drawing, another adaptation of the invention is illustrated. In Fig. 6, the impression surface of one die part 29 is shown, it being understood that the surface of the companion die part will be of the same construction in accordance with the teachings in Figs. 1 to 5 inclusive; therefore, the showing of the two die parts is not deemed to be essential. Arranged on the surface of each of the die parts in question is an impression 30 into which extends a cylindrical bore or passage 31 for the reception of a headed pin or other support that is partially indicated at 32 in Fig. 7 of the drawing, upon which one cast body 33 of the contour of the impression 30 is to be formed. Also opening into one side of the impression 30 is a gate or admission passage 34 which opens through one side of the die in an admission port 35 with which one injection nozzle 36 is adapted to register so that a heated thermoplastic material may be pressure discharged from the cylinder 37 into the port 35 and gate 34 and thus into the impression 30. The impression 30 is also preferably provided with a dove-tailed recess 30a centrally of one surface thereof to form on the resulting casting an anchor portion 33a for keying and positively retaining another cast body 38 on the body 33. The body 38 is formed in an impression 39 when one of the cast bodies 33 is arranged in said impression 39. A pin receiving passage 31a similar to 31 also extends into the impression 39, and a supplemental gate passage 34a extends into the impression 31a so as to receive the gate 40 which is integral with the body 33 when the latter is moved into the impression 39.

A gate or admission passage 41 is provided on the surfaces of the dies and opens into the impression 39 substantially in alignment with the passage 31 but at the opposite side of the die so as to extend to that part of the impression 39 which will form the cast body 38. Another nozzle 36a is adapted to register with the gate passage 41 so that heated casting material from a cylinder 37a may be pressure discharged into the impression 39 to form the cast body 38 simultaneously in forming the body 33 in the impression 30. In some instances, the pin 32 upon which the cast bodies are formed may be used as the ejector pin to remove the castings from the

dies when the latter are separated, and also to feed the castings. However, when forming castings on pins or other members of relatively light construction, it will be desirable to use an ejector or feed pin substantially similar to the pin 11. For this purpose, the adjacent surfaces of the dies are provided with a vertical passage 42 which extends into the gate passage 34 and another passage 43 which extends between the gate passage 34 and into the passage 41 so that both cast bodies will be supported on the pin employed, which is not shown, in ejecting the castings and also in feeding the castings the same as taught in Figs. 2 and 3 of the drawing. The lower surface of the dies is preferably recessed as seen at 44 to receive part of the cast bodies 33, 38 and to aid in supporting the same in the operation of trimming off the gate 40 and the gate 40a which extends to the body 38, both of which gates are indicated in dotted lines in Fig. 7, simply to show their relationship to the cast body prior to being trimmed off.

With the construction shown in Figs. 6 and 7 of the drawing it will be understood that one cylinder 37 will contain heated thermoplastic material of one color and the other cylinder 37a, similar material of another color, so that the resulting unitary cast member comprising the bodies 33, 38 will have the two distinct colors arranged thereon.

It will of course be understood that any desired contours may be provided in the impressions 30, 39 so long as the contours are such as to permit separation of the die parts employed for the ejection of the castings therefrom. It will also be apparent that when the ejector pin receiving apertures 42, 43 are employed, it is not essential that the apertures 31, 31a be employed, as the cast bodies may be formed the same as in the structure shown in Figs. 1 to 5 inclusive.

Having fully described our invention, what we claim as new and desire to secure by Letters Patent, is:

1. In a die casting machine, dies in which heated casting material may be pressure injected, said dies having adjacent abutting surfaces, each having two spaced impressions therein cooperating to form two spaced casting cavities when said dies are in closed position, gate passages extending along said surfaces from the exterior of said dies to each of said cavities, one of said cavities being larger than the other and having a contour such that a casting formed in said smaller cavity may be contained in said larger cavity when said dies are closed, said adjacent abutting surfaces of said dies also having recesses extending from said larger cavity to the exterior of said dies and positioned and arranged to receive at least part of the gate of a casting formed in the said smaller cavity when such casting is placed in said larger cavity.

2. In a die casting machine, dies in which heated casting material may be pressure injected, said dies having adjacent abutting surfaces, each having two spaced impressions therein cooperating to form two spaced casting cavities when said dies are in closed position, gate passages extending along said surfaces from the exterior of said dies to each of said cavities, one of said cavities being larger than the other and having a contour such that a casting formed in said smaller cavity may be contained in said larger cavity when said dies are closed, said adjacent abutting surfaces of said dies also having recesses extending from said larger cavity to the exterior of said dies and

positioned and arranged to receive at least part of the gate of a casting formed in the said smaller cavity when such casting is placed in said larger cavity, said gate passages being connected to each other along said adjacent surfaces.

3. In a die casting machine, dies in which heated casting material may be pressure injected, said dies having adjacent abutting surfaces, each having two spaced impressions therein cooperating to form two spaced casting cavities when said dies are in closed position, gate passages extending along said surfaces from the exterior of said dies to each of said cavities, one of said cavities being larger than the other and having a contour such that a casting formed in said smaller 15

cavity may be contained in said larger cavity when said dies are closed, said adjacent abutting surfaces of said dies also having recesses extending from said larger cavity to the exterior of said dies and positioned and arranged to receive at least part of the gate of a casting formed in the said smaller cavity when such casting is placed in said larger cavity, said gate passages being connected to each other along said adjacent surfaces, and said surfaces having ejector pin passages extending from the exterior of the dies to said smaller cavity.
